IMPROVEMENT IN HYDRANTS.

WALTER P. NEWHALL, OF NEW YORK, N. Y., ASSIGNOR TO HIMSELF AND
HARRIET A. DAVISON, OF THE SAME PLACE.

Letters Patent No. 60,230, dated December 4, 1866.

SPECIFICATION.

TO ALL WHOM IT MAY CONCERN:

Be it known that I, WALTER P. NEWHALL, of the city, county, and State of New York, have invented certain new and useful improvements in Street and Yard Hydrants, and do hereby declare the following to be a full, clear, and exact description thereof, reference being had to the accompanying drawings, and to the figures and letters marked thereon. Of these drawings—

Figure 1 represents an exterior side view of a hydrant containing my improvements.

Figure 2 is a vertical section view of the hydrant through the line *y y*, of fig. 1, showing the arrangement of the water pipes and their connection with the various troughs.

Figure 3 is a plan view of the hydrant.

Similar letters of reference indicate corresponding parts in the several figures.

Heretofore one class of hydrants have been constructed for certain uses, such as the supplying of water to fire engines, to sewers, and for street cleaning and sprinkling, &c.; and another class for furnishing the public generally with drinking water; to the latter is usually attached the tin cup or dipper-shaped vessel. The features of these two classes have not been before my invention combined in one and the same hydrant. Again, the necessity of providing for some of the domesticated animals, in an economical manner, and accessible at all times, a constant supply of cool water in our different cities and large towns, is obvious, but has been up to the present time overlooked. Now, the objects of my improvements in this regard are, first, to cause a hydrant to be so constructed that it may not only be used for fire engines and other purposes above mentioned, but, in addition thereto, furnish the public with drinking water, and, further, supply drinking water to horses, cows, dogs, and many other domesticated animals; second, in supplying the water in a manner that it will always be in a fresh and cool state; and third, in keeping the water at the base of the hydrant and below the fire-plug valve in a moving or live condition, so as to prevent its freezing in that vicinity during frosty weather.

To enable others to construct and use my improvements I will proceed to describe them.

A is the exterior casing of the hydrant, constructed in any convenient shape; B is the pipe through which the water is drawn from the street main in order to supply the hydrant. This pipe conducts the water into two branch pipes, C C, in the case of a double hydrant, as shown in the several figures. D is the fire-plug valve of the hydrant, operated by means of the rod and handle, E, when letting on or shutting off the water required for fire engines, &c. At a short distance below this fire-plug valve the pipe B is tapped, and a smaller pipe, F, inserted, which conducts the water up to the spout, G, from whence it flows into the first trough or basin, H, intended for the waste water from the spout and cup used by the drinkers. At the bottom of this trough or basin is inserted a small pipe, I, which passes down to the bottom of a large trough, J, situated on the opposite side of the hydrant at a lower level than the first-mentioned one. At a short distance below the top or rim of this trough, J, is placed an orifice to take the overflow off through the pipe, K, to supply the third trough, L, situated at a lower level than the trough, J, in the drawings, at the base of the hydrant. Near the top of this last referred to trough is placed another orifice to take the overflow off through the pipe, M, and into the gutter or street. This last trough is shown in the drawings as extending all round the hydrant. It may, however, especially if the hydrant is in close proximity to the gutter, extend only a portion of the whole distance around it. Such trough is intended to supply water for dogs, &c. The trough, J, is intended for horses, cows, &c., and for greater convenience, ought to be constructed on the side opposite to the waste trough or basin, H, face towards the middle of the street and project over the gutter. It can extend half the distance or so around the hydrant so as to permit of more than one animal drinking at the same time. The pipes leading between the several troughs are made of a sufficient size to permit of the overflow of water of one trough only filling the succeeding trough, without allowing the water to flow over the edge of the latter one. The water is permitted to flow up through the pipe, F, and then out of the spout, G, by turning a small stop-cock, 1, placed inside of the casing of the hydrant on the pipe near the neck of the spout, and supplies with the one stream the various troughs named, and thereby greatly economizing the water. The running stream is also changing the water in the various troughs by degrees, and thus tends to keep it fresh and cool. In frosty weather this running stream prevents the freezing of the water, just below the fire-plug valve, by keeping the water at that point in motion.

What I claim as my invention, and desire to secure by Letters Patent, is—

1. A hydrant in which two or more exterior basins at different altitudes are connected by pipes within the casing, substantially as described.
2. Combining a fire hydrant with the said hydrant, substantially as described.
3. Keeping the water in a live condition beneath the fire-plug valve D or cut-off, by means of the auxiliary induction pipe F, or its equivalent, substantially as described.

WALTER P. NEWHALL.
